AUTOMOBILE DOOR AND WINDOW CONSTRUCTION

Thomas W. Holt, Elkhart, Ind., and Roy T. Axe, Syracuse, N. Y., assignors to Excel Curtain Company, Elkhart, Ind., a corporation of Indiana

Application October 10, 1930. Serial No. 487,814

6 Claims. (Cl. 296—48)

This invention relates to automobile door and window constructions and particularly to constructions wherein the glass pane is held by a metal sash which is movable into and out of the door and has for its object a particularly simple and efficient means within the door for supporting the sash and holding it against rattling, particularly when the sash is elevated out of the door.

The invention consists in the novel features 10 and in the combinations and constructions hereinafter set forth and claimed.

In describing this invention, reference is had to the accompanying drawings, in which like characters designate corresponding parts in all 15 the views.

Figure 1 is a fragmentary elevation, partly broken away, of a door and sash embodying one form of this invention.

Figure 2 is a sectional view on line 2—2, Fig- 20 ure 1.

Figure 3 is an enlarged sectional view on line 3—3, Figure 1.

Figure 4 is a fragmentary elevation looking to the left of Figure 3.

Figure 5 is an enlarged sectional view on line 25 5—5, Figure 1.

Figures 6, 7, 8 and 9 are views similar to Figures 1, 2, 3, 4 and 5 of another form of this invention.

30 This invention comprises generally a hollow door body having a slot in its upper end, a sash movable into and out of the body and having depending extensions or tail pieces, means for supporting and guiding the sash, said means being located in the hollow body and coacting with the sash and tail pieces and compression devices in the hollow body and acting on the sash and the tail pieces when the sash is withdrawn wholly or part way into the hollow body and acting on 35 the tail pieces when the sash is fully raised.

1 designates the hollow door body, which may be of any conventional construction, it being understood that the door body includes an outer sheeting 2 and inner removable wall 3 and a top 45 strip 4 formed with a slot 5, through which the sash is movable.

6 designates the sash and the type here shown includes a pane of glass and also a marginal sash frame 7 usually formed up of sheet metal. The 50 construction of the sash forms no part of this invention. The sash is also formed with depending projections or tail pieces 8 these being for convenience in the form of a channel and being preferably extensions of the stiles of the sash 55 and in vertical alinement therewith.

The means for supporting and guiding the sash, in addition to the tail pieces which constitute portions carried by the sash, comprises channel shaped guide pieces 9 mounted in the hollow door and secured in position in any suitable 60 manner as by screws 10 extending through holes in the bottom of the guides 9 into blocks 11 within the hollow door adjacent the inner and outer edges thereof. The channel shaped guide pieces 9 terminate near but are spaced apart from the upper edge wall of the door body. The sash is raised and lowered by any suitable well known mechanism including rocker arms 13 actuated by a crank handle 14 and motion transmitting connections between the crank handle and said 65 arms, the arms having followers 15 slideable in a groove 16 along the lower edge of the sash. As the construction of the means for raising and lowering the sash forms no part of this invention, and as various forms of sash mechanisms are well 70 known, further description is thought to be unnecessary.

Insofar as this invention is concerned, it is merely necessary to bear in mind that the sash moves upwardly and downwardly out of and into 75 the hollow body.

The means for holding the sash against rattling, particularly when the sash is elevated comprises compression devices for holding the sash snugly in the channel shaped guide 9. The compression devices act on the tail pieces and the sash in one direction at an angle to the plane of the sash, these compression devices being yieldingly or spring supported. The compression devices are spaced apart along the guides 9 80 and the tail pieces, one at the upper end of each tail piece and the other toward the lower end. Also anti-friction devices are provided, paired with the yieldingly supported compression devices. Some or all the compression devices 85 may be carried by the tail piece and thrust against the guides, or by the guides and thrust against the tail pieces. In Figures 1 to 5 inclusive they are carried by the guides. In Figures 6, 7, 8 and 9, they are carried by the sash or tail piece.

17 and 18 designate respectively the yieldingly mounted compression devices mounted on each guide 9 and arranged to press the sash in a direction at a right angle to the plane of the sash, each of these compression devices consisting of a roller preferably of fiber or some non-metallic material carried at one end of an arm 19 extending lengthwise of one side of the channel 9 and pressed toward the sash by a flat or leaf spring 20. The flat or leaf spring 20 and the 100

arm 19 are secured at like ends to the channel as by rivets 21. The roller of the compression device 18 works through a slot 22 in the side wall of the channel 9. The roller of the upper compression device is located beyond the ends of the adjacent guides or channels 9 and as close as possible to the upper edge wall of the door body.

24 and 25 designate antifriction devices paired with or opposed to the compression devices 17, 18 and against which the sash and the tail pieces are thrust by the compression devices. These antifriction devices include rollers similar to the rollers of the compression devices and the rollers of the antifriction devices 24 are supported by rigid brackets at the upper end of each guide channel 9 to project beyond the end of said channel and being located as near as possible to the upper edge of the door channel.

20 Preferably additional means are provided for acting upon the sash and one of the tail pieces to thrust the sash edgewise in one direction and antifriction members are paired with the said compression devices located at the opposite edge 25 of the sash.

27 and 28 designate the compression devices carried by one of the guides 9 as the right hand guide, Figure 1, and located relatively to the sash, the tail pieces and the guide similar to the compression devices 17, 18, and being similar in construction to the compression devices 17, 18.

29 and 30 designate antifriction members co-acting with the left hand edge of the sash and paired with the compression devices 27, 28. These are similar in construction to the compression devices 24, 25 and similarly located with respect to the upper and lower ends of the channel guides 9.

40 In operation, the compression devices 17, 18 thrust the sash against the inner sides of the channel members 9 and the compression devices 27, 28 thrust the sash edgewise, thus holding the sash from rattling. Owing to the location of the compression devices and their coacting with the tail pieces, the compression devices also hold the sash against rattling when in raised position and also hold the sash in position so that it will snugly engage the door posts or pillars when the door is closed, in constructions where the sash, when elevated, closes against door posts or pillars.

By this construction, felt and rubber linings that otherwise become displaced during the raising and lowering of the window are eliminated or if used do not bear the brunt of the sliding action of the sash when being raised and lowered as the sash is supported and guided by the compression and antifriction devices.

60 In Figures 6, 7, 8 and 9 the compression devices are carried by the tail pieces.

31, 32 designate the compression devices for pressing the sash in one direction at a right angle to its plane. The devices 31, 32 are carried within each channel shaped tail piece 33 of the sash 34 and thrust against the side wall of each guide channel 35.

70 The compression devices 31, 32 are spring pressed rollers located within the tail pieces 33 and extending through slots 36 in one of the side flanges of each tail piece in order to thrust against the inner face of the side flanges of the channel shaped guides 35. The rollers 31, 32 are shown as carried at the free ends of flat springs 37 located within the tail piece 33 and fixed at their other ends to the side flange of the tail piece.

The rollers are here shown as of the anti-friction or ball bearing type. They are paired with incompressible rollers or antifriction members 38, 39 carried within the tail pieces 33 and extending through slots 40 in the opposite side wall of the tail piece to that in which the slots 36 for the rollers 31, 32 are located.

80 41, 42 are compression devices for thrusting the sash edgewise in one direction as to the left, Figure 6. These are spring pressed ball bearing rollers carried by one of the tail pieces and thrusting against the inner face of the bottom of the channel shaped guide 35. These rollers are shown as carried by leaf springs 43 secured to the tail pieces.

85 Fixed or unyielding rollers 44, 45 preferably of the ball bearing type are carried by the other tail piece that is the left hand tail piece, Figure 6, and coact with the bottom of the left hand guide 35. The operation of the form shown in Figures 6, 95 7, 8 and 9 is the same as that shown in Figures 1 to 5 inclusive except that the rollers move up and down with the sash, being self-contained therewith.

90 What we claim is:

1. In an automobile door and window construction, the combination of a hollow door body having a slot in its upper edge, a sash movable into and out of the door through said slot, the door being provided with guide pieces in the form of 105 channels within the same and the sash being provided with tail pieces below the lower edge of the sash and movable in said channels, means acting on said tail pieces at spaced apart points when the sash is raised for holding the sash from 110 rattling, said means thrusting on the tail pieces to press the same toward one side of the channel, and rolling antifriction means on the other side of the channel against which said tail pieces are 115 pressed.

2. In an automobile door, the combination of a hollow door body having a slot in its upper edge, a sash movable into and out of the body through said slot, guide channels mounted in the door body, compression devices located within the door body and coacting with the sash beyond the ends of the said channels and near the upper edge of the door body, and incompressible spaced apart devices paired with the compression devices for receiving the thrust of 125 the sash by the compression devices, said compression and incompressible devices acting to hold the sash against rattling in the channels.

3. In an automobile door and window construction, the combination of a hollow door body 130 having a slot in its upper edge, a sash movable into and out of the body through the slot, the body being provided with upright guides near its opposite edges and the sash having depending tail pieces coacting with the guides, spring-pressed compression devices acting on the tail pieces and the sash to support the sash and hold it from rattling in all positions thereof and incompressible devices paired therewith for receiving the thrust of the tail pieces and the sash by 140 said compression devices.

4. In an automobile door and window construction, the combination of a hollow door body having a slot in its upper edge, a sash movable into and out of the body through the slot, the body being provided with upright guides near its opposite edges and the sash having depending tail pieces coacting with the guides and spring-pressed compression devices including rollers acting on the tail pieces and the sash to support the 145 150

sash and hold it from rattling in all positions thereof, said compression devices acting in a direction edgewise of the sash and the tail pieces, and spring-pressed compression devices including 5 rollers acting on the sash and the tail pieces in a direction at a right angle to the plane of the sash.

5. In an automobile door and window construction, the combination of a hollow door body having a slot in its upper edge, a sash movable into and out of the body through the slot, the body being provided with upright guides near its opposite edges and the sash having depending tail pieces coacting with the guides and spring-pressed compression devices including rollers acting 10 on one of the tail pieces and the sash to support the sash and hold it from rattling in all positions thereof, said compression devices acting at spaced apart points in a direction edgewise of 15 the sash and the tail pieces, and spring-pressed compression devices acting at spaced apart points 20 on the sash and the tail pieces in a direction at

a right angle to the plane of the sash, and incompressible devices within the door body and paired with the compression devices for taking the thrust of the sash and tail pieces by the compression devices.

6. In an automobile door and window construction, the combination of a hollow body having a slot in its upper edge, a window sash movable into and out of the body through said slot, means for guiding the sash and supporting the same when in its extended position out of the door body, spaced apart compression devices located within the body and thrusting against the guide and supporting means in a resultant oblique direction thrusting the sash edgewise in one direction and in a direction at an angle to the plane of the sash and incompressible devices located within the door body and paired with the former compression devices for receiving the thrust of the compression devices.
